DESIGN FOR AN ASH RECEIVER

John D'Amaro, Brooklyn, N. Y., assignor to J.
Bennett Inc., Brooklyn, N. Y., a corporation of
New York

Application December 28, 1938, Serial No. 82,021

Term of patent 14 years

To all whom it may concern:

Be it known that I, John D'Amaro, a citizen of the United States, residing in the Borough of Brooklyn, county of Kings, city and State of New York, have invented a new, original, and ornamental Design for an Ash Receiver, of which the following is a specification, reference being had to the accompanying drawing, forming a part thereof.

Fig. 1 is a top plan view of an ash receiver showing my new design.

Fig. 2 is a side elevational view.

Fig. 3 is an end elevational view as shown on Fig. 2.

Fig. 4 is an elevational view of the opposite end.

I claim:

The ornamental design for an ash receiver, substantially as shown.

JOHN D'AMARO.
